FINGER RING

Filed June 25, 1927

INVENTOR

AARON ELKONIN

BY

Morris Kischtein

ATTORNEY

UNITED STATES PATENT OFFICE.

AARON ELKONIN, OF NEW YORK, N. Y.

DESIGN FOR A FINGER RING.

Application filed June 25, 1927. Serial No. 22,553. Term of patent 14 years.

To all whom it may concern:

Be it known that AARON ELKONIN, a subject of Russia, and resident of the city of New York, in the county of Kings, and State of New York, has invented a new, original, and ornamental Design for Finger Rings, of which the following is a specification, reference being had to the accompanying drawing, forming part thereof, in which the figure is an edge perspective view of a finger ring embodying my new design.

I claim:

The ornamental design for a finger ring as shown.

Dated New York city, June 22nd, 1927.

AARON ELKONIN.
